2 SHEETS—SHEET 2.

UNITED STATES PATENT OFFICE.

ROBERT E. NEILSON, OF TULSA, OKLAHOMA, ASSIGNEE, BY DIRECT AND MESNE ASSIGNMENTS, TO TULSA MACHINE AND TOOL COMPANY, OF TULSA, OKLAHOMA.

TEMPER-SCREW FOR WELL-DRILLING TOOLS.

1,400,900.

Specification of Letters Patent. Patented Dec. 20, 1921.

Application filed March 22, 1920. Serial No. 367,811.

To all whom it may concern:

Be it known that I, ROBERT E. NEILSON, a citizen of the United States, and a resident of Tulsa, in the county of Tulsa and State 5 of Oklahoma have invented certain new and useful Improvements in Temper-Screws for Well-Drilling Tools, of which the following is a specification.

My invention relates to improvements in 10 temper-screws for oil and other well drilling tools, and it consists in the constructions, combinations and arrangements herein described and claimed.

One of the foremost objects of the invention 15 is to embody improved constructions in a temper-screw so as to render the tool far more durable than ordinary temper-screws are known to be, many of the parts being interchangeable and quickly replaceable so that repairs can be rapidly made.

More specifically stated, a further object 20 is to provide a temper-screw in which the reins are reversible and interchangeable, and in which the head and jaw extensions to 25 which the reins are secured, are themselves replaceable in cases of breakage.

A further object of the invention is to 30 provide means, preferably springs, for automatically separating the screw jaws from the main screw when the associated clamp is undone for the release of said screw.

A still further object of the invention is 35 to provide removable bushings in the screw jaws, of a metal dissimilar to that of the main screw so as to avoid damaging the main screw in opening and closing the jaws.

A further object of the invention is to 40 provide an improved clamp yoke, which has flattened parts to prevent relative turning thereof on the screw jaws, in case the relatively light holding screw should snap off.

Another object of the invention is to 45 provide an improved cable supporting yoke in which the supporting link apertures are strengthened by extending lips, and in which laterally removable closure blocks are provided to enable the insertion of the links from the ends of the yoke upon removal of the blocks.

50 Other objects and advantages will appear in the following specification, reference being had to the accompanying drawings, in which:—

Figure 1 is a detail side elevation illus-

trating the application of the improved 55 temper-screw to the walking beam of a well drilling apparatus.

Fig. 2 is a vertical section of the improved 60 temper screw, parts being shown in elevation,

Fig. 3 is a front elevation of the temper screw,

Fig. 4 is a detail sectional view on the line 4—4 of Fig. 3, showing the springs for automatically separating the screw jaws 65 from the main screw when the clamp yoke is undone,

Fig. 5 is a detail horizontal section on the line 5—5 of Fig. 2, illustrating the construction of the clamp yoke and its mounting 70 on the screw jaws, parts of the yoke also being shown in section,

Fig. 6 is a detail perspective view of the removable screw bushings,

Fig. 7 is a perspective view of the temper- 75 screw head,

Fig. 8 is a perspective view of one of the screw jaws,

Fig. 9 is a detail perspective view of the upper ends of the reins, and 80

Fig. 10 is a perspective view of the improved cable supporting yoke.

The general arrangement of that part of a well drilling apparatus to which the improved temper-screw applies is clearly illustrated in Fig. 1 wherein the temper-screw generally indicated 1, is shown supported on the free end of the walking beam 2, which is pivoted on the headache post 3 and actuated by the ordinary bull-wheel 4.

The cable 5 is held by the gripping means 6, which in turn has links 7 which are carried by the cable supporting yoke 8. This yoke is more clearly shown in Fig. 10, and since it embodies features of improvement over 95 the ordinary cable supporting yokes, special mention is made thereof below.

It is the purpose of the temper-screw 1 to enable the slight lowering of the cable 5 and the tools attached thereto, at each stroke of the walking beam 2, this being accomplished through a complete turn of the main screw 9 by the operator in Fig. 1 at each stroke. When the main screw 9 has been fed out to the fullest extent, the clamp 10 is undone so that the screw jaws 11 separate, thus releasing the main screw and permitting the counter-weight 12 to pull it back 105

to the top. This is accomplished by means of the cable connections 13. Considering the parts of the temper-screw in regular order, attention is first directed to the head 14, which, although capable of being made in any desired manner and of any suitable material, is preferably cast in the vanadium steel since this particular material is renowned for its extreme toughness. Cylindrical arms 15 pivotally rest in appropriate sockets in the end of the walking beam, as is common in the art, but are provided with eyelets 16 in which the cable connections 13 are guided.

15 Relatively long depressions or recesses 17 in opposite sides of the head, terminate in smaller recesses 18 with interposed shoulders 19. The particular formation of the recesses and shoulders shown in Fig. 7, is of little consequence since they may be made otherwise than illustrated, their sole function being to receive and support the reins 20, the upper ends of which are shaped to precisely conform to the shape of the recesses and shoulders in the head 14. Fig. 9 shows the upper ends of the reins 20 to be recessed at 21 where the lugs or shoulders 19 come, and provided with lugs or shoulders 22 to fit in the recesses 18. The lower ends of the reins are made in precisely the same manner, and by reason of this construction the reins can be put in either way and can easily be replaced should a break occur.

35 The specific purpose of the lug and recess arrangements is to relieve the rein securing means 23 of undue strain. The securing means may be either bolts or rivets, either of which are easily removed when the occasion so demands. The lower ends of the reins are 40 secured in the screw jaws 11, (see Fig. 8,) which have extensions 24 with recesses 25, 26 and shoulders 27 identical in formation and purpose to the corresponding parts in the head 14. Recessed bosses 28 house expansion springs 29 for the purpose of separating the screw jaws from the main screw 9, when the screw 30 of the clamping yoke 10 is unscrewed to release the jaws from the main screw.

45 50 Bushings or boxes 31 in the screw jaws 11, are made of a metal dissimilar to that of the main screw 9 so that the danger of cutting or other mutilating of the main screw by the opening and closing movements of the jaws, is avoided. These bushings are internally square threaded to receive the square threads of the main screw. They also have ribs 32 to occupy grooves 33 in the jaws, and screws 34 to retain them in position.

55 60 The clamping yoke 10 embraces the lower ends of the screw jaws 11, the jaw at the right of Fig. 2 being recessed at 35, to receive that end of the yoke. Ordinarily, the screw 36 is sufficient to hold the yoke in place, but in order to anticipate the possible

loss or breaking of the screw 36, which would result in the shifting of the yoke on the screw jaws, the sides of the recess 35 are flattened at 37 (Fig. 5) to be engaged by shoulders 38 inside of the yoke and thus prevent possible relative turning.

70 75 The cable supporting yoke 8 embodies several novel features which are clearly illustrated in Fig. 10. It is loosely mounted on the lower end of the main screw 9, but in order to keep it from swinging around and perhaps striking the operator, a stay rod 39 (Fig. 1) is pivotally attached to the stay lug 40 at one side.

80 Any part of the well rigging will do as a place for mounting the other end of the stay rod, so long as this mounting will accommodate the up-and-down movement of the apparatus to which it is attached. Incidentally it is to be observed in Fig. 2 that 85 the cable supporting yoke 8 rests on the ball bearing 41 adjacent to the lower end of the main screw. The balls of this bearing are carried in a retainer ring which keeps them from dropping out should the yoke 8 by any 90 chance move up from the bearing.

95 100 Apertures 42 are occupied by the links 7 in Fig. 1, and in order to extend the supporting bases of the links, lateral lips 43 are formed on the yoke. The bottoms of the apertures and lips are curved to precisely conform to the curvature of the upper end of each link. By thus materially increasing the link supporting surface, the likelihood of link breakage due to the great strains, is materially reduced.

105 Closure blocks 44 are removable from the sides to admit the links to the apertures 42. When these are replaced and secured by the bolts 45, the yoke structure is completed so 110 that it appears practically integral. All that is required for the fitting of the bolts 45, is to drill a hole through each end of the yoke, the bottom of each being cored out to accommodate the head of the bolt.

115 120 No machine work is therefore necessary as is the case in similar devices on the market, which employ top closure plates which are screwed down. The use of screws means the boring and tapping of holes.

125 Referring again to the main screw 9, the upper end is provided with an elevator 46 which has a ball bearing mounting 47 (Fig. 2) on the screw. This elevator is nothing more than a cross piece extending at right angles to the reins 20, to the ends of which the cable connections 13 are secured. The purpose of the elevator, although indirectly referred to above, is made more clearly apparent in the operation of the temper-screw, which may here be briefly reviewed to advantage. The operator attends the drilling operation as in Fig. 1, and at the end of each stroke of the walking beam 2 and temper-screw 1, gives the screw handle 48 one 130

complete turn, thus letting the main screw 9 down a short distance.

While performing the drilling operation, the screw jaws 11 and bushings 31 are closed 5 on the main screw which, together with all of the drilling apparatus in the well bore, is supported by the screw jaws 11, reins 20, head 14, etc. All these parts together weigh hundreds of pounds and the provision of the 10 various recesses and shoulders 17, 18 and 19 in the head 14, and recesses 21 and lugs 22 on the reins, function to support the great weight imposed thereon and to relieve the fastening means 23 of undue strains.

15 The temper-screw is hoisted into position on the end of the walking-beam 2 by attaching the hoisting rope or other hoisting apparatus part to the ring 15^a in the middle of the head 14.

20 When the main screw 9 is completely let out in respect to the reins 20, the operator gives the screw 30 a number of turns to loosen the yoke 10, whereupon the springs 29 expand and force the screw jaws 11 from 25 the main screw 9. It is then that the weight 12 operates to pull the screw 9 and all attached parts up so that a grip by means of the instrument 6 may be gotten on the cable 5 in a new place.

25 It is necessary to repeatedly grip the cable in new places so as to accommodate the lowering or working down of the drilling implement at the bottom, by reason of the drilling operation. The interchangeable and 30 renewable functions of the various temper-screw parts should now be fully understood without requiring repetition.

I claim:—

1. A temper-screw, including a head suitably formed for support on a walking beam, 40 screw jaws adapted to engage a main screw, and connecting reins with end formations so associated with corresponding head and jaw formations, as to enable reversal and interchanging of the reins and individual replacements of the head and jaws.

2. A temper-screw, including a walking beam-supported head, and main screw-gripping screw jaws, both with shouldered recesses of like formation; and connecting reins with end formations fitting the recesses, all being of like contour to enable reversing or interchanging the reins or replacing the head and jaws individually.

3. A temper-screw, including a walking beam-supported head, and main screw-gripping means including separable screw jaws, both jaws and the head having shouldered recesses of like formation; and reins connecting the individual jaws to the head, suitable securing means being provided, said 55 reins having similar end formations providing independent supporting means relieving the strain on said securing means, and enabling reversal and interchange of the reins,

and replacement of either the head or individual jaws without disassembling other parts of the structure.

4. A temper-screw, including a pair of reins with end interrupted-edge formations 70 to provide locking devices, a walking beam-supported head with opposed-side recesses of contours corresponding to both rein-end formations to provide strain-relieving supports independent of rein securing means; and a two-part screw jaw, each part with an extension having opposed-side recesses like those in the head, to receive either end of either rein and to enable the easy removal of any rein-attached part.

5. A temper-screw supporting head, comprising a cross bar adapted for mounting on a walking beam, with end cable-guide eyelets; and recesses in opposite sides of the head, with shoulder formations to receive 85 and support similarly formed connecting reins.

6. A temper-screw, including a main cable-supporting screw, screw jaws, means for clamping them around the screw in normal 90 operation, including an embracing yoke suitably secured to one jaw, with auxiliary means preventing relative yoke-turning should the securing means fail, and a binding screw engaging the other jaw; means, including springs, for separating the jaws from the main screw when the binding screw is counter-turned, and means in connection with the main screw for then raising it in respect to the jaws, including cable and 95 weight connections.

7. A temper-screw, including a main screw, a pair of half-screw jaws, each with suitably mounted and affixed bushings of metal dissimilar to that of the screw, and 105 one with a recess terminating in flat ends, both having opposed sockets with expansion springs; and a yoke embracing the jaws, with a flat shouldered end seated in the recess in engagement with the flat ends and 110 suitably secured, said shoulders and flat ends preventing turning should the securing means fail, and a binding screw engaging the other screw jaw.

8. The combination in a temper-screw, of 115 a pair of screw jaws, with axially aligned and separated recesses housing expansion springs; a main screw centrally situated in respect to the jaws and springs, and clamping means co-operating with the springs in 120 opening and closing the jaws around the screw.

9. A temper-screw, comprising a head with opposite shouldered recesses, and extending pivot arms with cable eyelets; reins 125 secured in the recesses, with formations on each end like those of the recesses in the head; unthreaded screw jaws, with extensions having inside recess formations to receive the lower rein ends, one having a flat- 130

ended recess, and internal grooves; a main screw occupying half threaded bushings secured in the jaws, with ribs in the grooves, the screw having a ball-bearing swiveled cross bar at the upper end with cable connections running through the eyelets, the lower end having turning means with cable carrying means; and jaw clamping means including a yoke secured in the recess, with 5 flat shoulders engaging the flattened ends, and a binding screw opposing expansion springs operatively situated between the screw jaws.

10. In a temper-screw, a cable supporting yoke, with link apertures having lips ex-

tending laterally to widen the link supporting base.

11. In a temper-screw, a cable-supporting yoke, with link apertures and extending lips, both rounded in conformity with the shape 20 of a link, said apertures having horizontal link entrances; and closure blocks in the entrances, secured by bolts in drilled bores disposed vertically.

12. A temper-screw, including a cable-supporting yoke, with a lug for attachment of a suitably mounted stay bar, which prevents spinning of the yoke when the tension in an attached cable is lessened.

ROBERT E. NEILSON.
